DISPLAY CASE

William Templin, Glen Ellyn, Ill., assignor to
Briede & Rogovsky, Inc., Chicago, Ill., a cor-
poration of Delaware

Application February 13, 1933, Serial No. 656,550

5 Claims. (Cl. 190—16)

This invention relates to cases particularly intended for carrying or shipping samples or the like, and books or circulars to accompany the same and for displaying such samples. A particular use for which the invention is intended is in connection with samples or swatches of cloth for tailors or merchants taking orders for clothing.

The objects of this invention are to provide an improved case and display device of samples or the like; to provide a device of this character which may be carried and which may be set up on a table or stand to display the samples in an attractive manner; to provide a display case which may be opened to display a considerable number of samples in vertical position and other samples in horizontal position; and to provide such further advantages and improvements as will appear more fully from the following description.

20 In the accompanying drawing illustrating this invention,

Figure 1 is a front view of the case shown opened to display the samples;

Figure 2 is a plan view with parts broken away 25 to show the inner construction;

Figure 3 is an end view of Figure 1;

Figure 4 is an end view showing the case closed for carrying; and

Figure 5 is a detail showing the construction 30 of one of the dividing or partition members, and is taken on line 5—5 of Fig. 2.

My improved case as shown, comprises a body portion 6 having a bottom 7, rear wall 8 and end walls 9. The front wall 10 is hinged at 11 to the forward edge of the bottom 7 and is adapted to swing down as shown particularly in Figure 3, to expose the contents of the box or body portion. The body 6 has a longitudinal horizontal partition 12 which is spaced from the bottom 7 to provide a recess 13 for receiving style books, circulars or the like. The partition 12 has one or more slots 14 for receiving vertical plates or guides 15 which are preferably formed of sheet metal and which have flanges 16 engaging with the lower surface of the partition 12. These plates are securely held by means of rivets 17 which pass through the partition 12 and the flanges 16 as shown in Figure 5. In the arrangement shown, the plates or dividers 15 divide the body into three sections of suitable size for receiving samples or swatches as indicated at 18 which are piled loosely in the compartments and are readily visible and accessible to prospective customers.

55 The body is provided with a cover section 19

which is hinged thereto by hinges 20, the cover section also being recessed or in the form of a shallow box. The inner face of the top of the cover is provided with a plurality of fasteners or brackets 21 for holding swatches or samples mounted on cards 22. The brackets 21 comprise strips which are riveted to the cover and their ends 23 bent inwardly to embrace the sides of the cards as shown. The hinges 20 are provided with stops 24 so that the cover section will be held 10 approximately perpendicular as shown in Figure 3, so that the swatches secured therein will be plainly visible from in front of the case. Two wings or plates 25 are hinged at 26 to the sides of the cover section and are adapted to fold in 15 over the front of the cover section when the case is closed and to be swung out in alignment therewith when the case is opened to display position as shown in Figures 1 and 2. These wings or plates are also provided with brackets 21 and with 20 bottom brackets or supports 27 for holding cards 22 which will also be displayed in alignment with the cards in the cover section. The wings 25 are provided with any suitable fastener such as a hook 28 and button 29 for holding them in closed 25 position. The front wall or flap 10 is provided with a handle 30 and forms the top of the case when in closed position for carrying the same. This wall or top is also provided with catches or 30 fasteners 31 of any suitable type as for instance those ordinarily used for suit cases, which coact with complementary members 32 for holding the case closed.

The main portion of the case may be made of any suitable material but is preferably formed 35 of wood and covered with suitable fabric in order to make it durable and give it an attractive appearance.

The areas which are exposed when the case is opened to display position may be provided 40 with any desired advertising or descriptive matter and are preferably decorated to enhance the appearance of the case so that when the swatches and cards are positioned therein, the whole will present a pleasing appearance while 45 at the same time displaying the same in a convenient manner to be examined by prospective customers.

Having thus described my invention which I do not wish to limit to the exact form shown and 50 described except as pointed out in the following claims, I claim:

1. A carrying and display case for swatch samples, comprising a body portion with a hinged front adapted to be swung downwardly, a hori- 55

zontal partition in said body portion providing a compartment in the bottom of the body portion, dividers secured to the top of said partition to form compartments for holding swatches or the like, a cover hinged to the back of the body, means for holding the cover in substantially upright position, brackets in the cover for holding sample cards, wings hinged to the side of the cover, brackets on said wings for holding sample cards, fasteners for holding said wings in closed position, and fasteners for holding the front and cover in closed position.

2. A device as per claim 1 in which the partition is provided with slots, said dividers comprising plates extending through said slots and having flanges engaging with the partition and rivets for securing the flanges to the partition.

3. A display case for swatches, comprising a main body portion adapted to lie in a horizontal position when opened, means in the body portion for supporting a plurality of stacks of swatches, said body portion having a front which is hinged thereto and adapted to be swung downwardly to open position to expose the swatches.

25 a shallow cover hinged to the back of the body portion and adapted to be swung up to substantially vertical position, said cover having a plurality of centrally arranged fastening members for holding swatch cards in alignment in the cover, the sides of the cover further serving to support the cards therein, wings hinged to the ends of the cover and adapted to be folded in toward each other when the cover is closed and to be swung out into alignment with the cover

30 when the cover is opened, each of said wings having fastening means for holding swatch cards substantially in alignment with the cards in the cover, whereby all of the swatches will be displayed in a convenient and attractive manner.

4. A combined carrier and display case for tailor's swatches and other articles, comprising a relatively shallow body adapted to be positioned on its side for display purposes and having a hinged drop front adapted to be turned down when the device is to be used for display, a transverse partition in said body portion, a plurality of guides at right angles to the partition to divide the space for receiving a plurality of sets of swatches, a hinged cover for one side of the body portion which is adapted to be raised when the device is used for display purposes, means for holding said cover in raised position, means for securing a plurality of sets of swatch cards on the inner side of the cover, flaps hinged to the opposite sides of the cover which are adapted to be folded inwardly when the case is closed and to be swung outwardly for display purposes, and means for securing swatch cards to said flaps.

5. A display case comprising a main body portion adapted to lie in a horizontal position when opened for display purposes, means in the body portion for supporting and separating a plurality of articles to be displayed, a cover hinged to the back of the body portion and adapted to be swung up to substantially vertical position, said cover having a plurality of centrally arranged fastening members for holding display cards in alignment to the cover, wings hinged to the ends of the cover and adapted to be folded in toward each other when the cover is closed and to be swung out in alignment with the cover when the cover is opened, each of said wings having fastening means for holding display cards in alignment with the cards in the cover whereby all of the display cards will be displayed in a convenient and attractive manner.

WILLIAM TEMPLIN.
